(57) CLAIM

The ornamental design for padded volleyball leggings as shown and described.

DESCRIPTION

FIG. 1 is a front view of padded volleyball leggings showing my new design in a worn position;

FIG. 2 is a rear view thereof;

FIG. 3 is a right side view of the padded volleyball leggings in an unworn position;

FIG. 4 is a left side view thereof;

FIG. 5 is a top view thereof;

FIG. 6 is a front view of the padded volleyball leggings in a worn position wherein the leggings are knee length;

FIG. 7 is a front view thereof wherein the leggings are mid-calf length;

FIG. 8 is a front view thereof wherein the leggings are full length; and,

FIG. 9 is a front view thereof wherein the leggings are full length with stirrups.

The broken line outline of the partial human figure in FIGS. 1, 2, and 6-9 assists in illustrating how the padded volleyball leggings may appear when in a position of use, but forms no part of the claimed design. The broken line outline of various lengths of a garment in FIGS. 6-9 depict environmental structure to illustrate how the claimed design may appear when embodied to an article, but form no part of the claimed design.
